The ornamental design for a bioelectrochemical reactor, as shown and described.

DESCRIPTION

FIG. 1 is a perspective view of a bioelectrochemical reactor showing the new design;

FIG. 2 is a side view of the bioelectrochemical reactor of FIG. 1;

FIG. 3 is a side view of the bioelectrochemical reactor of FIG. 1 opposite the side view shown in FIG. 2;

FIG. 4 is an end view of the bioelectrochemical reactor of FIG. 1;

FIG. 5 is an end view of the bioelectrochemical reactor of FIG. 1 opposite the end view shown in FIG. 4;

FIG. 6 is a top view of the bioelectrochemical reactor of FIG. 1; and,

FIG. 7 is a bottom view of the bioelectrochemical reactor of FIG. 1.

(Continued)

The broken lines depict portions of the bioelectrochemical reactor that form no part of the claimed design.
